UNITED STATES PATENT OFFICE.

WILLIAM ISAAC RAVERT, OF HAZLETON, PENNSYLVANIA, ASSIGNOR TO STANDARD AUTOMATIC MACHINE COMPANY, OF PITTSBURGH, PENNSYLVANIA, A CORPORATION OF DELAWARE.

DESIGN FOR A CASING FOR VENDING-MACHINES.

51,393.

Specification for Design.

Patented Oct. 16, 1917.

Application filed August 24, 1917. Serial No. 188,077. Term of patent 14 years.

To all whom it may concern:

Be it known that I, WILLIAM I. RAVERT, a citizen of the United States, residing at Hazleton, in the county of Luzerne and State of Pennsylvania, have invented a new, original, and ornamental Design for a Casing for Vending-Machines, of which the following is a specification.

Referring to the drawings:—

Figure 1 is a perspective view of a casing for vending machines, looking at the front of the casing; and

Fig. 2 is a similar view looking at the rear.

I claim:

The ornamental design for a casing for vending machines, substantially as shown.

In testimony, that I claim the foregoing as my own, I have hereto affixed my signature in the presence of two witnesses.

WILLIAM ISAAC RAVERT.

Witnesses:
